UNITED STATES PATENT OFFICE.

JOHN E. MARSDEN, OF PHILADELPHIA, PENNSYLVANIA.

MOLDED-GLASS RECEPTACLE.

Application filed April 7, 1927. Serial No. 181,642.

This invention relates to the molding of plastic materials into predetermined shapes according to the form of the molds and has particular reference to the molding of large 5 thick or heavy glassware adapted for the holding of various commodities, but more particularly for storage battery purposes. Among the objects of the invention is to so practice the molding art as to produce a 10 heavy glass receptacle with a substantial uniformity of thickness or mass whereby the distribution of the glass will be equalized throughout the construction, so that the strain due to cooling or annealing will be 15 uniform, and to provide a cooling space for the glass after it is molded.

More specifically, in the construction of a unitary or solid glass receptacle for battery jar purposes, it is desirable to provide partitions for the making of separate cells and for said partitions to be integral parts of the receptacle. To accomplish this result it is 20 of course necessary to provide suitable flare not only for the receptacle itself, but for the 25 thickness thereof in the various parts and so under ordinary circumstances there would be certain portions of the receptacle, especially at the places where the partitions are united with the bottom, where there would 30 be a too great thickness of the glass with the tendency for undue stresses or strains in the finished commodity. By my improvement, however, I provide that there shall be 35 an approximation of uniformity of thickness of the glass even though the necessary taper or flare is observed.

With the foregoing and other objects in view the invention consists in the arrangement and combination of parts hereinafter 40 described and claimed, and while the invention is not restricted to the exact details of construction disclosed or suggested herein, still for the purpose of illustrating a practical embodiment thereof reference is had to the accompanying drawings in which like 45 reference characters designate the same parts in the several views, and in which—

Figure 1 is a vertical transverse section on the line 1—1 of Fig. 3 and including a 50 fragment of the mold and the receptacle in section.

Fig. 2 is a vertical transverse section on the line 2—2 of Fig. 3, a fragment of the receptacle being in place in the base plate 55 of the mold.

Fig. 3 is a plan view of the base plate and

valve, the side portions of the mold and the receptacle being omitted.

Referring now more specifically to the drawings, I show at 10 the mold base plate 60 having a vertical opening 11 therethrough in which is slidably and removably fitted what I term a valve 12, which like the base plate is of heavy cast metal such as cast iron so as to withstand the enormous pressures 65 brought to bear thereupon during the molding operations.

Fragments of the receptacle being molded are shown in Figs. 1 and 2 at 13, Fig. 1 showing at 14 a portion of one of the vertical partitions of which there are provided for three in the apparatus illustrated. The receptacle has a bottom or floor 15, the specific design or shape of which may be varied according to the finished product, but herein 70 illustrated as of substantially rectangular form, and provided with transverse upwardly extending channels 16, shown as two in number according to the number of partitions subdividing the receptacle into separate 75 cells. The partitions 14 extend upward in the same plane as the channels 16.

Extending longitudinally of the receptacle and from one partition to the next are a plurality of upwardly projecting mounds of 80 glass 17 which in a battery jar may be regarded as plate rests, and in the same vertical planes as these plate rests 17 are formed in the bottom surface of the bottom 15 a similar number of longitudinal channels or 85 grooves 18 shown best in Fig. 2 which indicates, furthermore, how the distribution of the glass and the consequent internal 90 strains or stresses thereon due to cooling or annealing are taken care of. The relation 95 of the channels 18 to the mounds or plate rests 17 as shown in Fig. 2 is practically the same as the relation of the channels 16 to the lower portions of the partitions 14.

Since the partitions 14 extend vertically 100 throughout the height of the receptacle and a considerable mass of glass would be inherent along the edges of the partitions or the unions between the partitions and the side walls of the receptacle under ordinary 105 circumstances, I provide, in order to reduce this mass of glass, a plurality of channels 19 extending vertically along the outer surface of the receptacle as shown clearly in Fig. 1 and by dotted lines in Fig. 2. These channels 19 taper upward toward the top edge 110 of the receptacle 13 and have their greatest

depth at the bottom of the receptacle where they merge into the horizontal channels 16.

The means illustrated for effecting the formation of the receptacle above described 5 include the formation of a seat 20 in the base plate 10 and entirely surrounding the vertical opening 11, and co-operating with this seat is the upper surface of the valve which is formed with a plurality of ridges 10 21 extending longitudinally thereof, the outer ends of these ridges registering with short horizontal ridges 22 extending across the bottom of the seat at the end portions thereof. As shown in Fig. 3 these longitudinal ridges 21 are disposed in pairs or in 15 a number corresponding to the number of longitudinal grooves or channels formed at 18 in the bottom of the receptacle and which channels are formed by said ridges in the 20 molding operation. Also the valve is provided with transversely and upwardly projecting ridges 23 intersecting the ridges 21 and which are responsible for the formation of the transverse channels 16 in the bottom surface of the receptacle.

At intervals along the side portions of the base plate seat are formed upwardly projected tongues 24 whose upper ends lie in the same plane as the top surface of the base 30 plate and which consequently register with a rib or tongue portion 25 of the side wall members 26 of the mold and from which result the formation of the side channels 19 which lie in the same plane as the partitions 14.

Agreeable to the usual molding operation of heavy glassware, the base plate 10 and valve 12 are suitably supported upon a base, not shown, and the side members 26 of the 40 mold are supported thereon and suitably

clamped together to receive the mass of molten glass and for the reception of the mold plungers likewise not shown but which form the complete receptacle. The several ridges and ribs of the apparatus disclosed 45 at the same time form the channels and grooves in the outer side walls and bottom surfaces of the receptacle. After the molding operation is completed the side portions 26 of the mold are detached and the valve 12 is forced upward with relation to the base plate 10, thereby stripping or separating the receptacle from the base plate, the receptacle being subjected at the proper time to the annealing and cooling operations.

I claim:

1. An article of molded glassware having an inner vertical partition therein leading upward from the bottom to the level of the top, and having a channel in the bottom surface of the bottom portion of the receptacle in the plane of said partition, whereby the mass of glassware at the bottom is accordingly reduced and distributed as to thickness.

2. A one-piece article of molded glassware having side walls and inner vertical partitions extending integrally upward from the bottom to the top thereof, and having vertical channels extending from the bottom all the way to the top along the outer surfaces of said side walls in the planes of said partitions.

3. An article as set forth in claim 2 in which a bottom channel is provided, the ends of which merge into the bottom ends of two oppositely disposed vertical side channels, all in the plane of a single partition.

In testimony whereof I affix my signature.

JOHN E. MARSDEN.
